Fig. 2

FIG. 1 is a perspective view of a tire showing my new design; and

FIG. 2 is an enlarged fragmentary side view of the shoulder region of the tire shown in FIG. 1.

It is to be understood that the tread pattern continues as shown throughout the circumference of the tire, and the tread shoulder on the side opposite the portion shown is a mirror image thereof.

The characteristic features of the design reside in the tread and tread shoulder portions of the tire.

I claim:

The ornamental design for a tire, substantially as shown and described.
